ATTORNEY

UNITED STATES PATENT OFFICE.

FRED DAY, OF ALCESTER, SOUTH DAKOTA.

CARBURETOR.

Application filed March 1, 1924. Serial No. 696,366.

This invention relates to carburetors, and the object is to provide a particular control of the valves by the float, and by reason of connections permitting reduced air pressure, under the conditions disclosed in the description of the construction in detail.

A further object is to provide an apparatus making unnecessary the use of a separate vacuum tank.

With the foregoing and other objects in view, the invention consists in the novel construction and arrangement of elements described, illustrated, and claimed, it being understood that modifications may be made within the scope of the claims without departing from the spirit of the invention.

In the drawings, Figure 1 is a view of the carburetor in vertical section; Figure 2 is a section of the hand operated element for controlling needle valve 88; Figure 3 is a detail view showing a port through the wall of chamber 63 at the lower right hand portion of Figure 1; Figure 4 is a section on line 4—4 of Figure 1; Figure 5 is a section on line 5—5 of Figure 4.

The main casing includes the upper section A and a lower section B, these sections being connected at C, and tapered portion H of the upper section fitting the lower section 30 at H', where there is a corresponding taper adjacent to the air inlet valve 66, referred to below. A float chamber 10 having walls 11 is spaced above the shell of the lower section B, and the gasoline passing from the float chamber into the bottom of section B enters the mixing chamber through the path to be described in more detail. Sediment is drained off when required at D. Gaskets E, F, G are located as shown, to prevent leakage.

Float 12 is rigid with stem 13 having a bore 14 in its lower end loosely fitting the reduced end 15 of a screw 16 holding a loosely mounted disk valve 17. This valve 17 closes ports 18 through which gasoline passes from chamber 10 to the bottom B' of section B. Disk valve 17 loosely fits bore 19, and screw 16 is provided with a shoulder 19' to prevent it from being screwed up against the valve. A gasoline intake duct 20 is connected with cap 21' of chamber 21, the cap having an angular portion (Fig. 2) for engagement by a tool, and duct 20 communicates with chamber 21 in which screen 22 is mounted. The fuel passes through port 23 to chamber 24, and to valve chamber 25

closed by a valve 26. This valve is triangular in cross section, has a tapered end seating at 27, and a rounded lower end engaged by arm 28 pivoted at 29. The arm is engaged by disk 30 on stem 13 of the float. Port P of Fig. 6 leads from chamber 63, and allows air displaced by the gasoline to pass out, so that the passage of fuel around valve 17 will not be obstructed. Overflow port P' 65 at the right of Figure 1 prevents an overcharge of gasoline, any surplus being allowed to run off.

A large valve 33 is slidable vertically on the stem 13 and loosely fits casing or chamber 34. This valve includes tubular portion 35 having an internal shoulder 36 engaged by coiled spring 37 located between the shoulder and disk 30. The spring, of the compression type, tends to raise valve 33, but failing to do so, disk 30 will strike the lower end of tubular member 35 and raise the valve.

Valve 33 has an upper bore 39 loosely receiving a valve 40 seated at 41 and controlling the admission of air through ports 42, bore 39 and ports 43 in tubular portion 35. Valve 40 is square in cross section, has an upper slot 44 for engagement by a tool inserted through an opening closed by cap 45, and this valve is threaded on to the upper end of stem 13.

Valve 33 seats at 33' having an upper flange 46 controlling the passage around the valve at the upper end of valve chamber 34.

Below cap 45 is a chamber 48 in communication with the outer air through ports 42.

In the side of valve chamber 34 is a port 49 communicating by means of duct or tube 50 with housing 51 of throttle valve 52, and on the side toward the engine. The stem 53 of this valve is controlled by arm 54, and a short arm 55 contacts with a screw 56 mounted in lug 57 and constituting an adjustable stop for the valve.

The main air intake 60 is in communication with chamber 61, partly rounded as shown, and separated by diaphragm 62 from lower chamber 63 in lower casing element B. Between chamber 61 and mixing chamber 64 is a valve seat 65 where a main valve 66 seats. This valve includes cylindrical portions 67, 68, the latter having ports 69 leading to chamber 64, and having threaded connection with the upper end of stem 70 provided with a longitudinal bore 71. A port 72 leads from this bore to space 71' and

registering ports 73, 74 lead to space 75 between cylindrical portion 67 and sleeve 76 having a reduced upper end threaded to stem 71. This sleeve 76 is concentric with stationary cylindrical element 78 on diaphragm 62, and element 78 guides stem 71, as well as the sleeve.

A stationary tubular member 80 incloses the lower part of stem 70, and a plug sleeve 81 is threaded into member 80, passing through the bottom B'. Elements 80 and 81 have registering ports 82, 83 permitting gasoline to enter the lower end of hollow stem 70 and pass upwardly to port 72. The lower end of stem 70 is smaller than sleeve 81 and includes a spiral rib 84 engaging stationary washer 85 and preventing vibration of the stem vertically.

Needle valve 88 controls port 72 in hollow stem 70 and is mounted in cylindrical member 89 having an upper flange engaged by coiled expansion spring 90 bearing on member 68 of valve 66. A controlling wire 91 engages member 89 and passes through tube 92 entering a plug sleeve 93 threaded into casing member A and retained by nut 94. Element or plunger 89 operates in bore 95 of member A of the casing. The tube 92 is retained by cap 96 threaded on to the end of sleeve 93 and acting to compress washer 97 against the tube. Element 93 has flat sides at one point, to permit of adjustment by a wrench.

Wire 91 is operated by knob or disk 100 rigid with stem 101 slideable in sleeve 102, the wire being retained in the stem by set screw 103 which forces the wire into recess 104. The head of the screw 103 engages a stud 105 under the action of spring 106, preventing displacement of the stem. A channel 107 in the stem permits the movement of the latter with reference to the stud and provides a guide. Tube 92 is connected with sleeve 102, in the manner shown at 108, the connection being similar to that at the other end of tube 92.

Needle valve 88 is therefore controlled by pressure or knob 100, by the operator,—the movement being transmitted through spring wire 91. The needle valve being gradually tapered as shown, permits of delicate control of port 72, admitting fuel.

Assuming that float 12 is down, valves 33 and 40 are closed, and the carburetor requires more gasoline,—engine suction through port 49 will draw in fuel through screen 22, and it will pass open valve 26 to float chamber 10, the suction in the latter holding lower valve 17 closed for the time.

Sufficient gasoline having entered, float 12 will rise, valve 26 will close, and small valve 40 on the stem of the float will open because of the rise of the float. Air will then pass through ports 42 and chamber 48,

through the bore around valve 40, and through ports 43 to chamber 10. The resulting elimination of suction will permit large valve 33 to rise under the action of its spring. Engine suction is however too strong to permit valve 33 to rise until air has entered through small valve 40 and relieved the suction, partially.

Suction on lower valve 17 being relieved, that valve will drop to open position, and allow gasoline to flow to B', and thence to ports 82, 83, and up through hollow stem 70.

After passing port 72 in stem 70 (the port being controlled by needle valve 88), the gasoline is mixed with air entering at 73, 74, 75, the mixture emerging through ports 69 into chamber 64, where it is further combined with air entering at 65 and passing large valve 66. From chamber 64 the fuel passes throttle valve 52 to the engine, and the speed of the latter and the suction produced determines the extent of opening of valve 66. When valve 66 rises, needle valve 88, or the reduced end thereof permits more gasoline to pass port 72, to meet the demands of the engine. For priming, pressure on knob 100 produces thrust on elements 91, 89 and 88 for the purpose desired.

What I claim is:

1. In a device of the class described, a float chamber, a float therein, a reduced air pressure connection for the chamber, a fuel inlet and an air inlet for the chamber, a tubular air inlet valve, a stem for the float, said stem passing through the valve, a valve on the stem controlling the passage of air through the tubular valve to the chamber, and controlling the movement of the tubular valve in one direction, and a spring for opening the tubular valve and admitting additional air to the chamber after the tubular valve has been released by the valve on the stem.

2. In a carburetor, a float chamber, a float therein, a reduced air pressure connection for the chamber, a fuel inlet and an air inlet for the chamber, a tubular air inlet valve, a stem for the float, said stem passing thru the valve, a valve on the stem controlling the passage of air thru the tubular valve to the chamber and controlling the movement of the tubular valve in one direction, a spring for opening the tubular valve and admitting additional air to the chamber after the tubular valve has been released by the valve on the stem, means for closing the fuel inlet valve upon the lifting of the float and stem, and means operated by the stem controlling the passage of fuel from the float chamber.

In testimony whereof I affix my signature.

FRED DAY.
